CONTROL APPARATUS

Walter S. Landon and Philip S. Russel, Detroit,
Mich., assignors to Detroit Lubricator Company,
Detroit, Mich., a corporation of Michigan

Application October 29, 1940, Serial No. 363,367

35 Claims.

(Cl. 158—28)

This invention relates generally to control apparatus and more particularly to means for controlling the flow of fuel and air to a fluid fuel burner.

An object of this invention is to provide a new and novel method of controlling the flow of fuel and air to a fluid fuel burner.

Another object is to provide correct combustion in a hydroxilation type burner during the step of changing the rate of combustion.

Another object is to provide means for reducing the size of the oil pool in a hydroxilation type burner prior to reducing the air supply to prevent a smoky flame.

Another object is to provide an intermediate step of operation in which the fuel flow is such that the burner will operate indefinitely without damage with either high fire or pilot fire air.

The invention consists in the new and novel cooperation of and combination of parts, to be more fully described hereinafter and the novelty of which will be particularly pointed out and distinctly claimed.

In the accompanying drawings, to be taken as a part of this specification, there is fully and clearly illustrated a preferred embodiment of the invention, in which drawings:

Figure 1 is a schematic view of the control system incorporated into an oil burning apparatus;

Fig. 2 is a simplified schematic view showing the wiring diagram for the control system;

Fig. 3 is a view in side elevation with certain of the parts broken away showing a control means embodying the invention;

Fig. 4 is a top plan view of the means of Fig. 3;

Fig. 5 is a view substantially along the line 5—5 of Fig. 4 looking in the direction of the arrows;

Fig. 6 is a view substantially along the line 6—6 of Fig. 4 looking in the direction of the arrows and with certain of the parts removed;

Fig. 7 is a partial view substantially along the line 7—7 of Fig. 4 looking in the direction of the arrows;

Fig. 8 is a view of certain of the parts showing their cooperative relationship;

Fig. 9 is a view in section of one feature of the invention, and

Fig. 10 is a diagrammatic view showing the invention connected into a burner control system.

Referring to Figs. 1 and 2 by characters of

reference, the numeral 1 designates the usual power line for supplying electrical energy to a manually operable double-pole single throw power switch 2. Lead wires 3, 4 connect the primary coil 5 of a step-down transformer 6 to the switch 2. A lead wire 7 connects one side of a transformer secondary or low voltage coil 8 of the transformer 6 to a contact member 9 of a room thermostat, diagrammatically shown at 10. The thermostat comprises a current conducting bimetallic blade 11 which carries and has electrically connected thereto, a current conducting spring member 12. Upon decreasing temperature of the air or other medium surrounding the blade 11 to a first predetermined temperature, a contact member 13 carried by the free end of the spring member 12 will be moved due to movement of the blade 11 toward the left so that member 13 engages the contact member 9 to complete a medium fire electric control circuit between the blade 11 and a lead wire 7. The spring member 12 flexes toward the blade 11 to move further toward the left upon subsequent decrease in temperature of the surrounding medium and the contact members 9 and 13 will be maintained in engagement at all blade temperatures below the first predetermined temperature irrespective of any movement of the blade 11. Subsequent to a predetermined decrease in temperature of the blade 11 below the first predetermined temperature, a contact member 14, shown as rigid with the blade 11, will engage a second stationary contact member 15 to close a high fire electric control circuit. It is to be understood, however, that any type of room thermostat which closes an electrical circuit at one predetermined temperature and closes a second electrical circuit upon the occurrence of a predetermined lower second temperature may be used. It is to be noted, however, that the thermostat must maintain the respective circuits closed at all temperatures below the temperature at which the circuit is closed. Preferably the contact members 9 and 13, and 14 and 15 should engage and break with a snap action. A thermostat similar to that shown, described and claimed by E. J. Dillman in a copending application, Serial No. 263,486, filed March 22, 1939, now Patent No. 2,255,021 granted Sept. 2, 1941, and assigned to the assignee of this invention may be used. By connecting the transformer secondary coil 8 to the contact member 9 instead of directly to the blade 11, the contact members 14 and 15 cannot act to close an electrical circuit if for some reason

the circuit is not first made between contact members 9 and 13.

The blade 11 is connected by a lead wire 16 to one terminal of a resistance heater 17 which acts upon energization to heat a bimetallic power element 18. The other terminal of the heater 17 is connected by means of a lead wire 19 to one terminal of a second resistance heater 20 which acts upon energization to heat a second bimetallic power element 21. A lead wire 22 connects the other terminal of the heater 20 to a horizontally extending movable switch arm 23, to be described more in detail hereinafter, which carries a contact member 24 normally held in engagement with a contact member 25 carried by a flexible or hinged electrical conducting arm 26. The arm 26 is electrically connected by a lead wire 27 to the transformer secondary coil 8 at the end opposite to that connected to the lead wire 7. The circuit just described constitutes the medium fire control circuit.

The contact member 15 is connected by means of lead wire 28 to one terminal of a resistance heater 29 which acts upon energization to heat a high fire bimetallic power element 30. The other terminal of heater 29 is connected by means of a lead wire 31 to one terminal of a resistance heater 32 which acts upon energization to heat and actuate a high fire air controlling bimetallic power element 33. A lead wire 34 connects the other terminal of the heater 32 to the lead wire 22 so that current can flow back to the secondary coil 8. The circuit just described is the high fire control circuit.

An electric motor, diagrammatically shown at 35, has a rotor 36 and a wound stator 37. The motor is preferably so constructed that it may assume a plurality of longitudinal positions to be described in more detail hereinafter. One terminal of the wound stator 37 is connected by means of a lead wire 38 to the lead wire 3 and the other terminal of stator 37 is connected by means of a lead wire 39 to a movable blade 40 of a diagrammatically shown single pole double-throw switch 41. The blade 40 carries upper and lower contact members 42, 43 which are positioned substantially in alignment one on either side of the blade 40. In the position shown the contact member 43 is in engagement with a contact member 44 carried by a hinged or flexible current conducting arm 45. The arm 45 is connected by a lead wire 46 to an auto secondary tap 46^a on the primary coil 5 so that reduced voltage is supplied to the motor 35. The contact member 42 is operable under certain conditions of operation to engage a contact member 47 carried by a current conducting resilient or hinged member 48. A lead wire 49 connects the member 48 to the lead wire 4 so that when contact members 42, 47 are in engagement and members 43, 44 are parted, full line voltage is placed on the stator 37.

The numeral 50 indicates the bottom wall of a liquid fuel chamber which has an outlet port 51 controlled by means of a reciprocally movable valve member 52 having a stem portion 53 which extends up through and is guided within an aperture in a rigid wall 54. The portion 53 has a shoulder 53^a adjacent its upper end and a flange 55 which is positioned intermediate its shoulder 53^a and the wall 54. A helical coil compression spring 56 is positioned concentric with the stem portion 53 intermediate the wall 54 and flange 55 and acts to urge the valve member 52 upward

away from the port 51 into an open position with the shoulder 53^a against a movable arm 57 of the bimetallic power element 18. Movement of the valve member 52 toward valve closed position by the element 18 is limited by engagement of the arm 57 with a lower flange portion of a low fire stop member 58. The member 58 is preferably screw-threaded into a rigid plate member 59 which has a fixed position relative to the wall 54 and port 51.

The element 18 is rigidly secured by means of a bracket 60 to a rigid plate or wall member 61 and the element 30 is rigidly secured by means of a bracket 62 to a rigid plate or wall member 63. When the element 30 is deenergized, an arm 64 thereof engages a lower flange of a medium fire stop member 65 threadedly secured to the plate member 59. Upward movement of the valve member 52 is limited by engagement of the shoulder 53^a with the arm 64 for medium fire position. A high fire stop member 66 is also threadedly secured to the plate member 59 and its lower end portion is engageable with the upper end of the valve member stem portion 53 to limit maximum or high fire opening movement of the valve member 52.

A reciprocally movable thrust member 67 is guided for vertical or longitudinal movement within apertures through the wall 54 and the plate member 61 and has a shoulder 68 adjacent its upper end portion which is engageable with the bottom surface of the lower flange portion of the stop member 58 to limit its movement in an upward direction under the influence of a leaf spring 69 and which action will be described more in detail hereinafter. The maximum downward movement of the thrust member 67 is limited by engagement of a lower shoulder 70 thereof with wall 54 but the shoulder 70 is preferably so positioned that within the desired range of adjustment of the low fire stop member 58 the arm 57 will be limited in its clockwise movement by engagement with the stop member 58 prior to engagement of the lower shoulder 70 with the wall 54. If it is desired that the adjustable range of the member 58 include full closed position, the shoulder 70 can never engage the wall 54 as long as the valve member 52 is in position. The thrust member 67 is continually urged in an upward direction by a component of force exerted by the leaf spring 69 which is transmitted to the member 67 through a thrust pin 71 having one of its conically shaped end portions in substantial point contact with the spring 69 and having the other of its conically shaped end portions in substantial point contact with a downwardly extending leg 72 of the movable blade 40. Because the point of engagement of the pin 71 with the leg 72 never passes below an imaginary line drawn between the pivot point of blade 40 and the point of engagement of the pin 71 with the spring 69, the blade 40 is continually urged by the spring 69 into engagement with the bottom end of the thrust member 67.

As is well known to those skilled in the art, when a bimetallic power element is heated or cooled the actuating portion thereof will tend to move in accordance with temperature change. The force exerted by the arm 57 of element 18 will be dependent upon the temperature of the element 18 and the position of the arm 57. If no external forces were applied to the arm 57 to prevent its free movement, for any given temperature of the element 18, the arm 57 would have

a definite position, but due to the external forces of the springs 56 and 69 the arm will not take a definite position with a given temperature of the element 18, i. e. the spring forces change with the spring movement and may build up or diminish disproportionately to temperature change acting on element 18. The bimetallic power element 18 being made of metal will have a definite modulus of elasticity and therefore a position assumed by the arm 57 under the influence of the springs 56 and 69 will cause an elastic or resilient force to be exerted by the element 18. The free position of the arm 57 is so chosen that when the element 18 is at room temperature, the arm 57 will be held in a displaced upward position resting upon the head or flange of the stop member 58 and will be exerting a downward force greater than the sum of the upward forces exerted by the springs 56 and 69. By this arrangement, the valve member 52 will be held in pilot fire position determined by the head or flange of stop 58 and the switch 41 will be held with the contact members 43, 44 in engagement during the periods when the element 18 is at room temperature. Thus, if the force exerted by the arm 57 in holding the members 52 and 67 in the position shown in Fig. 1 be decreased, there comes a time when the force exerted by arm 57 just equals the upward force exerted by springs 56 and 69. Upon a further decrease in force exerted by arm 57, the springs 56 and 69 will cause the arm 57 to rotate in a counter-clockwise direction. If the force exerted by the springs 56 and 69 remained constant during upward movement of arm 57, the arm 57 would assume a given position for every given temperature but in the instant arrangement the sum of the upward forces exerted by the springs 56 and 69 will vary depending upon the position of the members 52 and 67 so that the elastic or resilient force exerted by the arm 57 will vary. The spring 69 is so arranged and positioned relative to thrust member 67 that the force component exerted by spring 69 in a direction urging the thrust member 67 upward, continually increases from its initial movement upon upward movement of the member 67 and continually decreases upon downward movement of the member 67. The magnitude of this increase in the force component exerted by the spring 69 in urging the thrust member 67 upward is so proportioned that it is greater during each increment of movement than the sum of the increase in force exerted by the arm 57 due to the upward or counter-clockwise movement out of its temperature determined position and of the decrease in force exerted by the spring 56 due to its increase in length as it moves the valve member 52 upward to maintain its engaging relation with the arm 51. By proportioning or relating the forces as above set forth, it is possible for the parts and particularly the valve member 52 to be moved with a quick or snap acting movement from the position shown in Fig. 1 into an intermediate position or to a hesitation point in which the shoulder 68 is in engagement with the lower flange of the low fire stop member 58 at which position the upward component of force exerted by the spring 69 is absorbed by the stop member 58 and is ineffective to influence or to aid in the movement of the element 18 in a further upward direction. During this initial stage of upward movement which is prior to engagement of shoulder 68 with stop member 58, the downward force exerted by the arm 57 was somewhat less than the total of 75

the upward forces exerted by the springs 56 and 69 but considerably more than the upward force exerted by the spring 56 when acting alone. Therefore upon shoulder 68 engaging stop member 58 and before any subsequent upward or opening movement of the valve member 52 can occur, the downward force exerted by the arm 57 must be substantially reduced to compensate for the loss of the upward force exerted by the spring 69. This downward force of arm 57 is proportional to the temperature of the element 18 and, since it takes the heater 17 a period of time to increase the temperature of the element 18 and reduce its force to a pressure less than that of spring 56, the valve member 52 will be held in this intermediate position by the element arm 57 until such increase in temperature of the element 18 occurs. Further increase in temperature of the element 18 beyond that at which it balances or equals the force of spring 56 will cause arm 57 to gradually move counterclockwise until the shoulder 53^a engages arm 64 at which time further upward movement of the valve member 52 is prevented and any further counter-clockwise movement of the arm 57 will merely move the arm 57 away from the valve member and will not allow the valve member 52 to move any further toward open position. It may thus be seen that upon opening movement of the valve member 52, it is initially moved with a rapid movement into a low fire position intermediate the low fire position (the position shown in Fig. 1) and medium fire position and then after a predetermined time interval gradually moved from the intermediate position to the medium fire position. The thrust member 67 will move during the rapid initial movement of the valve member 52 with a quick movement into engagement with the stop member 58 to cause the contact members 43, 44 to part with a quick action and the contact members 42, 47 to engage to supply the stator 37 of motor 35 with full line voltage for medium fire air operation. Subsequent movement of the valve member 52 to medium fire position has no effect on the motor 35. The air supplying means comprises the motor 35 which propels a fan 15, shown as mounted on a motor shaft 16. A leaf spring 71 has one end secured to a member 78 which is positioned in fixed relation with the stator 37 and the other end of the spring 71 acts to urge the shaft 16 and the rotor 36 toward the left (see Fig. 1) so that the rotor 36 is held in a displaced position relative to the stator 37 at the reduced stator voltage provided when switch 41 is in the position shown. When full line voltage is applied to the stator, i. e., when the switch 41 is in its other position, the solenoidal force of the stator 37 will pull the rotor 36 toward alignment with the stator 37 against the force of spring 71 and the speed of rotation of the rotor 36 will also be increased. The shaft 16 extends from the rotor 36 through an aperture in a damper 79 and is shown as having a flange or head portion 80 which is engageable with the damper 79 upon movement of the rotor 36 toward alignment with the stator 37 to rotate the damper 79 about its fulcrum 81 until a lower edge 82 of the damper 79 engages an arm 83 of the power element 33. The cold or deenergized position of the arm 83 is regulated by engagement with the upper surface of a flange portion of a stop member 84 which is threadedly secured to a wall member 85 which is in a fixed position relative to the fulcrum 81. The arm 83 acts upon engagement of the edge 82 to limit its

movement to the position at which the correct air will be supplied for the fuel admitted by the valve member 52 at medium fire position with the shoulder 53 against arm 64 and with the element 38 deenergized or at room temperature. The damper 78 is so arranged relative to its fulcrum point that the area of the damper 78 below the fulcrum 81 is greater than the area above the fulcrum 81 so that the suction caused by the fan 75 will tend to rotate the damper 78 to the position shown in full line (see Fig. 1). Should the fan 75 stop due, as for example, to a burned-out motor the suction effect of the fan 75 will cease and due to the balance of the damper 78 it will swing to the dotted line position (see Fig. 1). It will be noticed that the upper portion of the damper 78 is bent inwardly. This accomplishes a two-fold purpose of balancing the damper for movement into the dotted line position and also of allowing sufficient air to bypass the damper 78 for forced draft low or pilot fire operation when the fan is operating as shown.

The element 33 has a definite operating characteristic relative to the element 38 so that upon energization of the resistance heaters 28 and 32, which are in series circuit, the arm 83 will be moved against a stop member 86 prior to movement of the arm 64 to allow movement of the valve member 52 to high fire position. One way in which this may be accomplished by using similar elements and heaters is by so arranging the element 33 that when it is at room temperature or deenergized, the arm 83 engages the stop member 86 very lightly and by choosing the element 38 so that when it is at room temperature or deenergized the arm 64 engages the stop member 85 with a much greater force. In this way a relatively small increase in the temperature of the element 33 will cause the arm 83 to move against stop member 86 while a much greater temperature increase of element 38 will be required to move the arm 64 away from the stop member 85. Other means could be employed such as using heating elements with different heating effects or by insulation.

The element 21 is positioned so that it is cooled in some manner by the air stream from the fan 75 and as shown the element 21 is supported by means of a support 87 within an outlet duct 88 which transmits the air from the fan 75 to a burner 89, diagrammatically shown. The burner 89 is supplied with fuel by means of a conduit 90 which leads from the outlet port 51 to the burner 89. Should the air output from the fan 75 fail or fall below a predetermined minimum for any reason, the element 21 will be heated by the resistance heater 20 so that the arm 81 will move downwardly beyond the end of a downwardly extending leg 92 of a bell-crank lever 93 fulcrumed as at 94. The switch arm 23 forms the other leg of the lever 93. A spring or other urging means 95, which is shown as being positioned intermediate the top wall 96 of the duct 88 and the horizontally extending switch arm 23, acts to pivot the lever 93 in a counter-clockwise direction to part the contact members 24 and 25 upon movement of the arm 81 beyond the end of leg 92. Counter-clockwise movement of the lever 93 is limited by engagement of the arm 23 and a head portion 98 of a manually reset member 99 and engagement of the head portion 98 with a rigidly positioned wall member 99a. Opening of the contact members 24, 25 acts to deenergize the resistance heaters 17, 20, 28 and 32 so that the elements 18, 21, 30 and 33 will return to their

deenergized positions and the valve member 52 and the fan 75 will therefore be set for low fire operation. Once the lever 93 has moved to tripped position it will remain in that position until the reset member 99 is pushed downward to allow the arm 81 to slide into the position shown (see Fig. 1) with its end in engagement with the leg 92.

Fig. 2 is a simplified diagrammatic view of the electrical circuit of Fig. 1 and like parts are designated by like numerals and a further description thereof is deemed unnecessary.

Figs. 3 through 9 show a commercial construction embodying features of this invention. The numeral 100 designates generally a housing comprising an upper casing 101 and a lower casing 102 detachably secured together by means of screws 103. The lower casing 102 has a bottom wall 104, an open top and a continuous side wall which encloses a chamber 105. Liquid fuel is supplied from a suitable source of supply (not shown) through an inlet 106 leading into a strainer chamber 107 which may be integral with the bottom wall 104. From the chamber 107, the strained liquid fuel flows into the chamber 105 through any of the usual valve members actuated by suitable means and well known to the prior art so that a substantially constant liquid fuel level is maintained in the chamber 105 at the lever L-L. Extending upwardly from the wall 104 into the chamber 105 is a boss 108 which has two longitudinally extending passageways 109, 110 which open together at their intersection below the line L-L and open downwardly through the wall 104 into a hollow outlet 111 which may be internally threaded for receiving a conduit from a fuel burner (not shown). The passageway 109 extends upwardly through the boss 108 and opens through the top wall thereof above the line L-L. The passageway 110 also extends upwardly through the boss 108 and opens through the top wall thereof but the passageway 110 is communicatively connected to the chamber 105 for liquid fuel flow from a point below the line L-L throughout the remaining upper portion of the passageway 110 by means of a longitudinal slot 111a extending through the wall of the boss 108 into the passageway 110. The passageway 110 has three different internal diameters from its lower to its upper end and a plurality of shoulders 112, 113 are formed at the intersection of the different diameters. Press-fitted within the passageway 110 and seating against the shoulder 112 is a tubular seat member 114 having an orifice 115 and a seating surface 116. Liquid fuel from the chamber 105 flows through the slot 111a and through the seat member 114 into the passageway 110 to flow through the outlet 111 to the fuel burner (not shown). The rate of liquid fuel flow is controlled by means of a valve member 117 which has a reduced diameter portion 118 and a conic portion 119 connecting the reduced portion 118 with the normal diameter portion. The valve member 117 has a longitudinal central passageway 119a extending therethrough which has its upper end portion opening radially outward into the chamber 105 above the lever L-L and has its lower end opening through the lower end portion of the member 117 into the seat member 114 below the orifice 115. The reduced portion 118 is reciprocally slidable within the orifice 115 in piston-tight relationship and has a V-shaped slot 120 which adjustably registers with the ori-

face 115 for controlling flow of liquid fuel from the chamber 105. Fuel is prevented from flowing except through the slot 120 by the piston fit of the portion 118 in the orifice 115 and upon movement of the valve member 117 to its lowermost position, the conic portion 119 engages the seat member 114 to completely stop the flow of fuel from the chamber 105. The passageways 109 and 119^a act to maintain atmospheric pressure or the same pressure which exists above the fuel in chamber 105 within the outlet 111 so that the only force acting to promote flow of fuel from the chamber 105 is the liquid fuel head itself.

The valve member 117 has a stem portion 121 which extends upwardly through the chamber 105, through an aperture in a bottom wall 122 of the upper casing 101. A split ring 123 is rigidly secured to the stem portion 121 within the chamber 105 and serves as one abutment for an end member 123^a which is concentric with and loosely fits the portion 121. A helical coil spring member 124 is concentric with the stem portion 121 and is under compression between the shoulder 113 and the member 123^a and urges the member 123^a against the ring 123. The spring member 124 normally acts to urge the valve member 117 in an upward direction away from the orifice 115 and surface 116. The aperture through the wall 122 is preferably of suitable size so that the valve member 117 and its attached ring 123 may be removed upward therethrough. Upon removal of the member 117 the member 123^a engages the under surface of the wall 122 to hold the spring 124 from passing through the aperture.

The casing 101 has a front side wall 125 which extends upward from the bottom wall 122 approximately one third of the distance to the open top wall 126 of the casing 101 and has a plurality of rear walls 127, 128 which extend upwardly from the wall 122 and are joined at one end portion to end walls 129, 130, respectively, of the casing 101. The walls 127, 128 each extend toward each other and the walls 127, 128 each terminate approximately one third of the distance from the respective end walls 129, 130 to which it is joined to the respective opposite end walls 130, 129. A U-shaped wall member has the open end of its parallel side walls 131, 132, respectively, secured to the facing end portions of the walls 127, 128, respectively, and has its connecting or rear wall 133 extending vertically to and upwardly from the wall 122 substantially along its longitudinal centerline. An L-shaped member, to be described more in detail hereinafter, is secured with its horizontal bottom or base portion 134 in engagement with the top edge of the side wall 125 and with one side edge portion flush with its outer face. The portion 134 extends substantially parallel with the bottom wall 122 and has the opposite side edge portion abutting the wall 133. A vertical end portion or wall 135 of the L-shaped member has its front edge portion flush with the outer face of the wall 125 and its rear edge portion engaging the wall 131 with the outer face thereof substantially flush with the outer face of the wall 131. High voltage and low voltage terminal strips 136, 137, respectively, extend parallel with the wall 122 and are held against the upper edge portions of the walls 125, 127 and 125, 128, respectively, by screws 138, 139, respectively, threaded into bosses 140, 141, respectively, which extend upward from the bottom wall 122. It may now be seen that the upper casing 101 is di-

vided into a transformer compartment 142, a high voltage terminal compartment 143, a low voltage compartment 144, and a switch compartment 145.

5 A transformer 146 is held, as by screws 146^a, to the wall 133 and has low voltage lead wires 147, 148 leading to the low voltage terminal strip 137 and high voltage lead wires 149, 150, 151 leading to the high voltage terminal strip 136. The lead wires 150, 151 are connected to the end points of the transformer primary coil while the lead wire 149 is connected to the primary coil at an intermediate point thereby making the primary coil serve the dual purpose of its usual function and also serving as an auto-transformer. The high voltage terminal strip 136 comprises a strip of insulating material in which are secured four terminals 152, 153, 154 and 155. The lead wires 149, 150 and 151 are connected respectively to the terminals 152, 153 and 154. Electrically connected to the terminal 155 and secured to the insulating material strip is one end of a resilient switch blade member 156 having a blade portion 156^a extending longitudinally of and normally urged toward the insulating strip which carries oppositely facing contact members 157, 158. The contact members 157, 158 cooperate respectively with stationary contact members 159, 160 positioned respectively above and below the longitudinally extending portion of the blade member 156 to form a single pole double-throw switch. The contact member 160 is electrically connected to the terminal 152 and the contact member 159 is electrically connected to the terminal 153. 35 Main lead wires (not shown) conduct electrical energy from a suitable source of supply (not shown) and are connected to the terminals 153 and 154. Lead wires 159^a and 159^b connect the terminals 154, 155 to the controlled electrical apparatus 160^a, diagrammatically shown in Fig. 10, and which may be a blower fan to supply the necessary air for combustion of the liquid fuel discharged from the chamber 105.

The low voltage terminal strip 137, like the strip 136, comprises a substantially rectangular plate-like member 161 which may be "Bakelite" or other suitable insulating material. The strip 161 has its ends substantially registering with and resting on the upper edge of the walls 125, 128 with one side edge conforming with and positioned against the end wall 130. The other side edge 162 of the member 161 fits snugly against the wall 132 and has a portion 163 which extends therefrom to the wall 125 and which portion 163 is spaced from the end edge 164 of the L-shaped member bottom portion 134. Secured to the top face 165 of the member 161 are seven terminals 166, 167, 168, 169, 170, 171 and 172. The low voltage lead wires 147, 148 extend through an aperture in the wall 132 and are connected to the terminals 167, 168, respectively. A bus bar 172^a has one end secured to the terminal 166 and extends along the top face 165 beyond the end of the wall 132 adjacent the portion 163 where a finger portion 173 is bent downward beyond the edge portion 163 toward the bottom wall 122. A second bus bar 175 is secured to the terminal 172 and extends therefrom along the top face 165 toward the edge portion 163 where a finger portion 176 is bent downward beyond the portion 163 intermediate the finger portion 173 and the wall 125. A third bus bar 177 is secured to the terminal 171 and extends therefrom along the top face 165 toward the edge portion 163 where a finger portion 178 is bent downward beyond

the edge portion 163 intermediate the finger portions 173 and 176.

A medium fire power element 179 and a high fire power element 180 have their supporting members 181, 182, respectively, secured to the upper surface of the L-shaped member portion 134. The power elements 179, 180 preferably are similar to those in the copending application of Walter S. Landon, Serial No. 339,427, filed June 8, 1940, and comprise cylindrical portions 183, 184, actuating or movable portions 185, 186 and resistance heaters 187, 188, respectively. The movable portions 185, 186 have V edges which overlie and engage an upwardly facing shoulder 189 of the valve member stem portion 121 which extends upward through an aperture in the portion 134. Normally, when the power elements 179, 180 are deenergized, the movable portions 185, 186 are urged in a downward direction to move the valve member 117 toward closed position. Movement of the portion 186 in a downward direction is limited by engagement thereof with a flange 190 of a stop member 191 screw-threaded to a plate member 192. The member 192 is positioned substantially parallel to and spaced above the portion 134 and is held in place by a plurality of screws 193 against the top ends of a plurality of cylindrical members or bosses 194 which may be cast integral with and which extend upwardly from the portion 134. To add strength to the bosses 194 and for convenience in casting they may be joined together by webs 195.

A tab 196 extends downwardly from the lower face of the portion 134 and has an aperture for receiving one end of a fulcrum pin 197. A second tab 196^a, which may be in the form of a longitudinal reinforcing rib extending downwardly from the lower face of the portion 134, is spaced from the tab 196 and has an aperture aligned with the aperture in tab 196 for receiving the other end of the pin 197 about which is fulcrumed a bifurcated end 198 of a lever member 199. The member 199 extends along, beneath and adjacent, the lower surface of the portion 134 and terminates in a downturned portion 201 which has an indentation 202, the purpose of which will be hereinafter described. Secured to the lever member 199, adjacent the portion 201, is an insulating strip 203 which extends beyond the end of the lever member to engage the upper surface of the blade member 156 so that the lever member 199 is operable upon counter-clockwise rotation (see Fig. 6) to move the switch blade member 156 downward to cause the contact members 157, 159 to break circuit and the contact members 158, 160 to make circuit. Secured to the wall 135 and extending downward therefrom toward the bottom wall 122 is a leaf spring 204 which has at its lower end portion an indentation 205 spaced toward the wall 129 from the indentation 202. The indentation 205 is positioned so that when the lever member 199 is above an imaginary line drawn between the indentation 205 and the fulcrum pin 197. A thrust member 206 has its opposite end portions pointed and one received within each of the indentations 202, 205. The member 206 is longer than the normal distance between the indentations and acts to flex the spring 204 away from the component of force on the lever member 199. The force exerted by the spring 204 is adjusted by means of a screw 206^a which adjusts the position of leaf member 206^b having an inturned engaging portion 206^c. After adjustment the screw 206^a is preferably soldered in position at the factory, as at 206^d, to

prevent unauthorized tampering by inexperienced persons.

Intermediate the portion 201 and the fulcrum pin 197 the lever member 199 has a rounded 5 raised portion 207 which underlies an aperture 208 through the base portion 134. A thrust member 209 has a pair of spaced, upper and lower shoulders or strip members 210 which are rigidly held in fixed relation to each other and which 10 have a connecting portion reciprocally guided within an aperture 211 through the plate member 192. The lower end of the thrust member 209 has a flange portion 212 which is received within and guided in the aperture 208 and the lower 15 surface of the portion 212 engages the raised portion 207 so that as the thrust member 209 is reciprocated between the fixed limits as determined by the shoulders 210 the lever member is 20 rocked to cause the blade member 156 and contact 25 members 157, 158 to make and break their respective circuits. A collar member 213 is adjustably screw-threaded to the thrust member 209 intermediate the plate member 192 and base portion 134 and has a shoulder portion 214 30 against which the V edge of the movable portion 185 engages. The upper end of the thrust member 209 has a screw-driver slot 215 so that the thrust member may be rotated thereby to move the collar member 213 longitudinally thereof. 35 The collar member 213 is held against rotation with the thrust member 209 due to engagement of a flat side wall surface portion 215^a which upon attempted rotation thereof engages the side edge portion of the movable portion 185. In this manner the maximum downward movement of the actuating portion 185 is determined and also the minimum fuel controlling position of the valve member 117. A helical coil spring 216 is 40 positioned concentric with the thrust member 209 with its end portions engaging the flange portion 212 and the lower end surface of the collar member 213 to prevent unwanted rotation of the thrust member 209 during operation of the control means. The extreme upward or opening 45 movement of the valve member 117 is limited by engagement of the top end of the stem portion 121 with a high fire adjustment screw 217 which is screw-threadedly secured to the plate member 192 in alignment with the longitudinal axis of 50 the valve member stem portion 121. Unwanted rotation of the screws 217 and stop member 191 are prevented by nuts 218 which are threaded to the screw 217 and member 191 respectively below the member 192 and hold spring disk members 55 219, which may be members similar to lock washers, under stress against the lower surface of the member 192. A locking member 220 is held, as by a screw 221, to the plate member 192 and has a bifurcated portion engaging the nuts 218 to 60 hold them against rotation with the member 191 and the screw 217 during manual rotation thereof for medium and high fire adjustment.

The heaters 187, 188 have lead wires 222, 223, and 224, 225, respectively, which extend downward through apertures in the base portion 134 of the L-shaped member and are connected to suitable terminals 226, 227 and 228 carried on the lower face and adjacent one edge 229 of a rectangular block 230. The block 230 is 65 preferably moulded from "Bakelite" with a central recess 231 opening through an end edge 232 opposite to edge 229 so that the block 230 will fit over the lever member 199 and block 230 may be secured, as by screws 233, to the lower face of the base portion 134. Lead wires 222 and 224 are

connected to the terminal 226 while lead wire 223 is connected to terminal 227 and lead wire 225 is connected to terminal 228. Each terminal 226, 227 and 228 has respectively secured thereto one end of contact strip members 234, 235 and 236, respectively. The members 234, 235 and 236 extend beyond and are bent upward along and spaced from the edge 229 and have their upwardly extending end portions rounded and bent inwardly against the edge 229 so that the strip members may rock about their rounded edges thereby to align themselves for good contact relationship respectively with the finger portions 173, 176 and 178 with which they cooperate in a manner which may best be seen by reference to Figs. 8 and 9. Due to manufacturing tolerances and errors when the base portion 134 is placed in position the strip members 234, 235 and 236 may not be in exact parallel relation with the finger portions 173, 176 and 178 respectively so that a good electrical connection will not be made therebetween. The finger portions 173, 176 and 178 are therefore so arranged relative to the strip members 234, 235 and 236 that they engage prior to movement of the base portion 134 into its proper position with apertures 237 and 238 in the base portion 134 in alignment with screw holes 239 and 240, respectively, in upwardly extending bosses from the wall 122. Therefore as the flat-headed screws 241, 242 are screwed downward into the holes 239 and 240 from the position shown in Fig. 9 the tapered screw head portions will cam in the similarly tapered portions of the aperture 237 or 238 to slide the base portion 134 to the right (Fig. 8) thereby causing the strip members 234, 235 and 236 to rock on their rounded ends until the engaging portions align themselves with the respective finger portions 173, 176 and 178.

Fig. 10, which shows a diagrammatic showing of the apparatus connected to an oil burner system, like parts have been designated by like numerals. A room thermostat, diagrammatically shown at 250, has a medium fire contact member 251 and a high fire contact member 252 which are connected respectively by lead wires 253, 254 to terminals 168 and 170. An electric conducting temperature sensitive element 255 is connected by a lead wire 256 to the terminal 169 and has secured thereto a leaf spring 257 which carries a contact member 258 which is operable at a predetermined temperature of the element 255 to be moved thereby into contact relationship with the contact member 251 to complete an electrical circuit. A contact member 259 is carried directly by and is operable to be moved by the element 255 into contact relationship with the contact member 252 to complete an electrical circuit upon a predetermined temperature of the element 255 below that at which the members 251 and 258 engage. An electrically operated air controlling means, diagrammatically shown at 260, has one terminal connected by a lead wire 261 to the terminal 172 and its other terminal connected by a lead wire 262 to the terminal 170. A bimetallic operated electric switch 263 has one terminal connected by a lead wire 264 to the terminal 166 and its other terminal connected by a lead wire 265 to the terminal 167. An electrical heater 266 is positioned relative to the switch 263 so that when the air supplied to the burner by an electrically operated fan means 160^a is reduced below a predetermined desired quantity, it is operable to heat the switch 263 and cause it to open the circuit between the lead wires 264 and 265 there-

by to deenergize the secondary circuit of the transformer 146. One terminal of the heater 266 is connected by a lead wire 268 to the terminal 169 and the other terminal of the heater 266 is connected by a lead wire 269 to the terminal 171. If desired a safety control, indicated diagrammatically at 270, may be used to deenergize the secondary circuit of the transformer 146 upon a dangerous operating condition such as excessive temperature of the medium heated by the burner.

The operation of the apparatus shown in Figs. 1 and 2 is as follows: Electrical energy flows from the source of supply through the power line to the switch 2. From the switch 2 it flows through lead wire 3 through the transformer primary 5 and lead wire 4 back to the switch 2 and to the source of supply through the power line 1. The stator 37 of the fan motor 35 is supplied with reduced voltage through the switch 41 from the auto-tap 46^a and the fan 75 is rotated at reduced speed. The spring 77 is acting on the motor shaft 76 to urge the rotor 36 toward the left (see Fig. 1) against the solenoidal force of the stator 37. Movement of the rotor 36 to the position shown allows the damper 79 to be pulled toward closed position due to the suction of the fan acting on its larger lower area. The clearance about the upper end of the damper 79 is sufficient to allow only sufficient air to be drawn in by the fan 75 when operating at reduced speed, to burn the pilot fire fuel which is being admitted to the burner 89 by the valve member 52. The dotted line position of the damper 79 indicates its position when the fan 75 is not operating and only natural draft is supplying air to the burner 89. This is an emergency condition which will occur only in the event of a power failure or in some failure of the fan 75 or motor 35.

Upon a reduction of the temperature of the blade 11 contact member 13 will engage the contact member 9 to energize the medium fire circuit as follows: current flow from the secondary coil 8 through lead wire 7, contact members 9 and 13, member 12, blade 11, lead wire 16, heater 17, lead wire 19, heater 20, lead wire 22, contact members 24, 25 and lead wire 27 to the secondary coil 8. The heater 17, being energized, heats the element 18 which acts to reduce the downward force exerted by the arm 57. At a predetermined reduced downward force of the arm 57, it is moved upward by the spring 69 acting through the thrust pin 71 and the spring 56 acting through the members 52 and 67. Upward movement which occurs with a quick action due to the increasing upward component of force exerted by the spring 69 is limited by engagement of shoulder 68 with the stop member 58. At the same time the valve member 52 and member 67 are moved upward the switch 41 is caused to break the circuit through contact members 43, 44 to cause the contact members 42, 47 to engage and supply full line voltage to the stator 37. At full line voltage, the stator 37 exerts sufficient pull on the rotor 36 to urge it against the force of the spring 77 more nearly into alignment with the stator 37. Movement of the rotor 36 toward alignment with the stator 37 causes the portion 80 to rock the damper 79 until the edge 82 engages the arm 83 at which time further longitudinal or axial movement of the rotor 36 is prevented. Increased air for medium fire operation is now being supplied while the fuel flow is increased only to an intermediate flow which is determined by the distance the member 67 can

move prior to engagement with the stop member 53. Continued heating of the element 18 causes the downward force exerted by the arm 57 to be gradually reduced and the valve member 52 to move gradually toward medium fire position and which position is determined by engagement of the shoulder 53^a with the arm 64. The position of arm 64 is determined by the stop member 65. Should the increased air supply fail, the heater 20 will act to heat the element 21 and the arm 91 will move downward beyond the end of the leg 92 so that the spring 95 will act to rotate the bell crank lever 93 and part the contact members 24 and 25 thereby deenergizing any and all of electrical circuits supplied by the secondary coil 8 and sending the burner to pilot fire operation.

Should the temperature of the blade 11 decrease to a predetermined lower temperature, the contact members 14 and 15 will engage and energize the high fire control circuit as follows: Current flows from the secondary coil 8 through lead wire 7, contact members 9 and 13, member 12, blade 11, contact members 14 and 15, lead wire 28, heater 29, lead wire 31, heater 32, lead wire 34, contact members 24 and 25 and lead wire 27 back to the secondary coil 8. Energization of the heater 32 causes it to heat the element 33 and gradually move the arm 83 into engagement with the stop member 86 thereby to allow the rotor 36 to move further into alignment with the stator 37 and the damper 79 into high fire air controlling position with the edge 82 in engagement with the arm 83. Energization of the heater 29 causes it to heat the element 30 and gradually reduce the downward force of the arm 64 so that the spring 56 will gradually move the valve member 52 upward into high fire fuel flow position in engagement with the stop member 66. The element 33, as was hereinbefore described, will act to increase the air flow to high fire air flow more rapidly than the element 30 increases the fuel flow so that excess air will be supplied during the period of increasing fuel flow. Should the air supply be reduced for some reason so that the arm 91 is moved downward due to the heating effect of the heater 20 and the contact members 24 and 25 separate, the high fire circuit will be deenergized as well as the medium fire circuit.

Upon breaking of the high fire circuit the elements 30 and 33 will cool and gradually return to the positions shown in Fig. 1 and move the damper 79 and the valve member 52 to the medium fire controlling position. It is to be remembered, however, that movement of the valve member 52 toward medium fire position will be sooner than movement of the damper 79 to medium air controlling position, as was set forth hereinbefore, so that excess air is supplied during this period of transitory operation. Upon breaking of the medium fire circuit the heater 20 and element 21 begin to cool with no beneficial result being produced and the heater 17 and the element 18 begin to cool. Cooling of the element 18 causes an increased downward force to be exerted by the arm 57 which will gradually move the valve member 52 toward closed position and the shoulder 53^a away from the arm 64. This movement occurs gradually until the arm 57 engages the thrust member 67 at which time further downward movement of the arm 57 and the valve member 52 ceases until the element 18 cools to a predetermined lower temperature. Upon attaining this predetermined lower temperature the arm 57 will then move the valve

member 52 and switch member 41 to the pilot fire position with a snap action as was hereinbefore described. The predetermined lower temperature is so chosen relative to the temperature at which the arm 57 engages the member 67 that the time necessary for the element to cool is more than a sufficient time for the fuel pool in the burner 89 and/or the excess oil in the conduit 90 to be burned so that fuel is being burned in the burner at the intermediate rate which is determined by the intermediate position of the valve member 52 with the medium fire air supply. In this manner the burner is prevented from smoking due to the presence of too much fuel for the amount of supplied air and as the intermediate fuel supply is so chosen that a sufficient quantity of fuel is being supplied to the burner to prevent the excess air from drawing the flame down into the bottom of the burner pot a damaging burner condition is prevented. It has also been found that such an intermediate fuel flow will burn without smoking with pilot fire air supply and therefore when the switch 41 is moved with a quick action to supply reduced voltage to the stator 37 and the valve member 52 is moved with a quick movement to pilot fire fuel supplying position a non-damaging large pilot flame occurs which gradually reduces itself to the small pilot flame which burns after equilibrium conditions have been reached.

The operation of the device shown in Figs. 3 to 10 is as follows: In the position shown in Fig. 10, the burner system is operating at pilot fire and the element 179 is at room temperature with its movable portion 185 urging the valve member 117 to minimum pilot fire flow position, this minimum flow position being determined by the engagement of the movable portion 185 with the collar member shoulder portion 214 and of the upper spaced shoulders 210 with the top surface of the plate member 192. The thrust member 209 in this position is engaging the rounded raised portion 207 and holding the lever member 199 in its counter-clockwise position so that the strip 203 is holding the blade member 156 in its down position and contact members 158 and 160 are in engaging relation. The fan means 160^a is in this position of the blade member 156 being supplied with reduced voltage from the transformer 146 for reduced speed operation.

As the temperature of the space being heated by the burner decreases in temperature, the element 255 of thermostat 250, which is positioned in the heated space, will move toward the right (see Fig. 10) and at a predetermined temperature the contact member 258 will engage the medium fire contact member 251 to energize the medium fire control circuit. Current now flows from the secondary coil of the transformer 146 through lead wire 148 to the terminal 168. From terminal 168 the current flows through lead wire 253, contact members 251, 258, spring 257, element 255, and lead wire 256 to the terminal 169. From the terminal 169 the current flows through lead wire 268, heater 266, lead wire 269, terminal 171, bus bar 177, lead wire 223, heater 187, lead wire 222, bus bar 172^a, terminal 167, lead wire 264, switch 263, lead wire 265, terminal 167 and through lead wire 147 back to the secondary of the transformer 146. Energization of this medium fire circuit acts to cause the heater 187 to heat the portion 183 of the element 179 with a consequent movement of the movable portion 185 upward with a snap action far enough to allow the thrust member 209 to move upwardly until the lower shoulder 210

engages the under face of the plate member 192 and to allow the valve member 117 to move upward or toward valve open position the same distance between the upper and lower shoulders 210. The snap movement is due to the relationship of the inherent tendency of the resilient blade 156 to move upward, the changing component of force exerted by the spring 204 through the thrust member 206, and the force exerted by the spring 124. The springs 124 and 204 and the resiliency of the blade 156 and element 179 are so chosen that the increase in the component of force exerted by the spring 204, acting through the thrust member 206, the lever member 199 and the member 209 to move movable portion 185 in an "up" direction (see Fig. 6) increases upon movement of the lever member 199 in the clockwise direction more rapidly than the arithmetic sum of the decrease in forces exerted by the spring 124, resilient blade member 156 and the increase in force due to the resiliency of the element 179 when the parts move from the position shown in the drawings to the position just described and which is designated as the transitory or hesitation position. Engagement of the lower shoulder 210 with the bottom surface of the plate member 192 absorbs any extra upward force exerted by the thrust member 209 and any further opening or upward movement of the valve member 117 is dependent upon the upward force exerted by the spring 124 and the downward force exerted by the element 179 and therefore there is a time lapse while the heater 187 heats the cylindrical portion 183 to a predetermined higher temperature before the valve member will continue to move upward to medium fire position which is the position in which the shoulder 189 engages the movable portion 186 of the element 180. This position of medium fire operation or engagement of the shoulder 189 with portion 186 is determined by the setting of the member 191. At the time the thrust member 209 moves the lower shoulder 210 into engagement with the plate member 192 the blade member portion 156^a parts the contact members 158, 160 with a quick action and causes the contact members 157, 159 to engage with a quick action to place full primary line voltage on the fan means 160^a to increase its speed of operation and consequently increase its air delivery to the fuel burner. Concurrently with the energization of the heater 187 the heater 266 which is in series circuit therewith is also energized and acts to heat the bimetallic switch 263 in an effort to cause it to move to open circuit position. The length of time needed for the heater 266 to cause the switch 263 to open is, however, so chosen relative to the length of time necessary for movement of the thrust member 209 to its upper position with consequent increase of voltage to the fan means 160^a that the heater 266 will not open the switch 263 prior to the normal movement of the member 209. As soon as the increased output of the fan means 160^a occurs the temperature of the heater 266 and/or switch 263 will be prevented, due to the increased air flow, from rising to the necessary high temperature to cause the switch 263 to open and the burner apparatus will continue to operate at medium fire position indefinitely. However, if through some faulty mechanism the air supply is not increased to that necessary to maintain the burner at satisfactory medium fire operation and the temperature of the heater 266 and/or switch 263 falls below the opening temperature, the switch 263 will open and act to return the burner apparatus to pilot fire

position. The switch 263 is preferably of the manual reset type and as it will not automatically return to closed position, manual closing is necessary and the operator is consequently notified of a fault in the burner apparatus.

Should the medium fire output of the burner be insufficient to maintain the temperature in the heated space, and the temperature falls to a predetermined lower temperature, the contact members 259, 252 will be brought in engagement to energize the high fire circuit as follows: Current flows from the secondary of the transformer 146, through lead wire 148, terminal 168, lead wire 253, contact members 251, 258, spring 257, element 255, contact members 259, 252, lead wire 254, terminal 170, lead wire 262, the air controlling means 260, lead wire 261, terminal 172, bus bar 175, lead wire 225 heater 188, lead wire 224, bus bar 172^a, terminal 166, lead wire 264, switch 263, lead wire 265, terminal 167 and through lead wire 147 back to the secondary of the transformer 146. Energization of the high fire circuit causes the heater 188 to heat the portion 184 thereby to gradually raise the movable portion 186 so that the spring 124 can move the valve member 117 to high fire position in engagement with the high fire adjustment screw 211. At the same time the heater 188 is heating the portion 184 the air controlling means 260 is energized. The action of the means 260 is, however, somewhat faster than the action of the element 180 and the air supply is increased for high fire operation more rapidly than the fuel supply is increased.

As the space temperature increases the contact members 252, 259 will break the high fire circuit allowing the heater 188 and portion 184 to cool so that the movable portion 186 moves the valve member 117 toward medium fire position. Upon deenergization the means 260 is slower to act than the element 180 so that the fuel supply is reduced prior to the reduction of the air supply. As the space temperature increases a further predetermined amount the contact members 251 and 258 break the medium fire circuit to deenergize the heater 187 and heater 266. As the heater 187 and portion 183 cool the movable portion 155 moves downward gradually moving the valve member 117 toward closed position until the portion 185 engages the shoulder 189 at which time further downward movement of the movable portion 185 is opposed by the upward forces acting on the thrust member 209. This increase in opposing force to downward movement of the portion 185 causes it to hesitate at the intermediate fuel flow which is determined by the setting of the collar member 213 on the member 209 and the distance between the spaced shoulders 210. The fuel flow in this hesitation position is preferably such that the excess pool of fuel in the burner to be burned and/or any excess fuel in the fuel line intermediate the outlet 111 and the burner can flow to the burner and be burned, without a smoky flame and also is such a flow that with medium fire air the flame will not be driven down into the burner with prolonged operation subsequent to burning at the intermediate fuel rate of flow. The total force acting upward on the member 209 is so related to the characteristics of the element 179 that the time interval necessary for the element 179 to cause further downward movement of the valve member 117 after engagement with the shoulder 214 and downward movement of the member 209 is more than sufficient to burn the oil pool in the burner and/or the

excess oil in the oil line leading to the burner from the outlet 111. Subsequent to this predetermined time the movable portion 185 will move with a snap action the thrust member 209 downward until the upper shoulder 210 engages the top surface of the plate member 192 and also the valve member 117 downward a like amount thereby regulating the oil flow for pilot operation and the fan means 160^a for slow speed low air delivery operation.

What is claimed and desired to be secured by Letters Patent of the United States is:

1. The method of regulating the ratio of fuel to air to a burner between predetermined upper and lower combustion limits which includes the step of maintaining maximum fire air supply for the upper limit while maintaining a reduced fuel flow at a constant rate during a transitory interval while changing from the upper to the lower limit.

2. The method of controlling the supply of air and the supply of fuel to a burner during reduction of the burner flame from a higher to a lower flame which comprises, reducing the rate of fuel supply to an intermediate rate while maintaining the rate of air supply substantially constant, maintaining constant the ratio of the reduced rate of fuel flow to the air supply for a time interval, and then reducing the rate of air supply and further reducing the rate of fuel supply.

3. The method of reducing a burner flame from a high fire to a pilot fire which comprises, maintaining a substantially constant air supply suitable for the high fire, reducing the rate of fuel supply, maintaining substantially constant the rate of flow of the reduced fuel supply while maintaining the constant air supply, and then reducing the air supply and further reducing the fuel supply to provide a proper fuel to air ratio for the pilot fire.

4. The method of controlling the supply of air and the supply of fuel to a burner during reduction of the burner flame from a higher to a lower flame which comprises, reducing the rate of fuel supply to an intermediate rate while maintaining the rate of air supply substantially constant, maintaining constant the ratio of the reduced rate of fuel flow to the air supply for a predetermined substantially constant time interval, and then simultaneously reducing the rate of air supply and further reducing the rate of fuel supply.

5. The method of controlling the supply of air and the supply of fuel to a burner during reduction of the burner flame from a higher to a lower flame which comprises, reducing the rate of fuel supply to an intermediate rate while maintaining an excess rate of air supply, maintaining substantially constant the ratio of the reduced rate of fuel flow and the excess rate of air supply for a time interval, and then reducing the rate of air supply and further reducing the rate of fuel supply.

6. The method of reducing the supply of air and the supply of fuel to a fuel burning apparatus having inherently a lag between the time the fuel flow is reduced by a control means and the time when reduction of the quantity of fuel in the burner pot occurs which comprises, reducing the rate of fuel supply to a substantially constant lower rate at the control means while maintaining the rate of air in excess of that required by said reduced lower rate of fuel, maintaining said reduced lower rate of fuel and said excess air until the fuel is being consumed at the reduced lower

rate, and then reducing the rate of air supply and further reducing the fuel supply.

7. The method of reducing the supply of air and the supply of fuel to a fuel burning apparatus having inherently a lag between the time the fuel flow is reduced by a control means and the time when reduction of the quantity of fuel in the burner pot occurs which comprises, reducing the rate of fuel supply at the control means to a substantially constant lower rate while maintaining the rate of air substantially constant, maintaining said reduced lower rate of fuel flow and said constant rate of air for a predetermined time interval, and then reducing the rate of air supply and further reducing the rate of fuel supply for a desired fuel to air ratio for low fire operation.

8. The method of reducing the supply of air and the supply of fuel to provide a lower flame in a fuel burner having a fuel pool and having means for supplying air to the burner under pressure which comprises, reducing the rate of fuel flow to the pool and maintaining a rate of air supply in excess of that required for combustion of the fuel in the pool, and after the pool has been reduced to a quantity commensurate with a reduced supply of air then supplying fuel at a further reduced rate for a further reduced pool and reducing the rate of air supply for combustion of the reduced pool.

9. The method of reducing the supply of air and the supply of fuel to provide a lower flame in a fuel burner having a fuel pool and having means for supplying air to the burner under pressure which comprises, gradually reducing the rate of fuel flow to the pool and maintaining a rate of air supply in excess of that required for combustion of the fuel in the pool, and after the pool has been reduced to a quantity commensurate with a reduced supply of air then reducing the rate of air supply and the rate of fuel supply substantially simultaneously and with a quick action to a proper fuel to air ratio for proper combustion and the formation of a reduced pool.

10. The method of reducing the supply of fuel and the supply of air to a fluid fuel burner having high, medium and low rates of heat output and having means for supplying air to the burner under pressure which comprises, reducing the rate of fuel supply from the rate of fuel supply necessary for the high rate of heat output to a medium rate of fuel supply necessary for the medium rate of heat output while maintaining a rate of air supply in excess of that required for combustion of the reduced rate of fuel supply, reducing the rate of air supply to that rate desired at said reduced rate of fuel supply, maintaining this desired ratio of fuel and air as long as it is desired to operate the burner at the medium rate of heat output, after the desired medium rate of heat output is no longer desired further reducing the rate of fuel supply to a rate necessary for a heat output intermediate the medium and the low rate of output of the burner while maintaining for a predetermined time substantially the same rate of air supply which was required for the medium rate of heat output, and then substantially simultaneously reducing the rate of air supply and further reducing the rate of fuel supply for a desired fuel to air ratio for the low rate of heat output.

11. The method of increasing the supply of fuel and the supply of air to a fluid fuel burner having means for supplying air thereto under

pressure which comprises, increasing the rate of fuel flow to an intermediate rate and increasing the rate of air flow to the rate necessary for a proper fuel to air ratio at a desired rate of fuel flow higher than the intermediate rate of fuel flow, maintaining the intermediate rate of fuel flow and the increased rate of air flow for a time interval, and then increasing the rate of fuel flow to the desired higher rate of fuel flow.

12. The method of increasing the supply of fuel and the supply of air to a fluid fuel burner having means for supplying air thereto under pressure which comprises, quickly increasing the rate of fuel flow to an intermediate rate and substantially simultaneously increasing the rate of air flow to the rate necessary for a proper fuel to air ratio at a desired high rate of fuel flow, maintaining the intermediate rate of fuel flow and the increased rate of air flow for a time interval, and then gradually increasing the rate of fuel flow to the desired high rate of fuel flow.

13. The method of increasing the supply of fuel and the supply of air to a fluid fuel burner having means for supplying air thereto under pressure which comprises, increasing the rate of fuel flow to an intermediate rate and increasing the rate of air flow to the rate necessary for a proper fuel to air ratio at a desired high rate of fuel flow, maintaining the intermediate rate of fuel flow and the increased rate of air flow for a time interval, then increasing the rate of fuel flow to the desired high rate of fuel flow, and upon failure of the rate of air supply to increase the increased rate after a predetermined time interval, reducing the rate of fuel flow to the original low rate.

14. In an oil burner control system, means movable in two directions for controlling flow of fluid fuel, means for moving said means, means for limiting movement of said controlling means in one of said directions thereby to allow a minimum predetermined flow of fuel to the burner for low fire operation, said moving means being operable to move said controlling means in a second direction for increased flow of fuel to the burner, means limiting movement of said controlling means in said second direction for determining a predetermined higher flow of fuel to the burner, and means operable upon movement of said controlling means in one of said directions and at a fuel flow intermediate to said predetermined minimum flow and said predetermined higher flow to cause said controlling means to hesitate for a predetermined time in its movement.

15. In an oil burner control system, means movable for controlling flow of fluid fuel, means for moving said means in one direction, means for limiting movement of said controlling means in said one direction thereby to allow a minimum predetermined flow of fuel to the burner for low fire operation, means for moving said controlling means in a second direction for increased flow of fuel to the burner, means limiting movement of said controlling means in said second direction for determining a predetermined higher flow of fuel to the burner, and means operable upon movement of said controlling means in one of said directions and at a fuel flow intermediate to said predetermined minimum flow and said predetermined higher flow to cause said controlling means to hesitate for a predetermined time in its movement.

16. In an oil burner control system, means

movable for controlling flow of fluid fuel, means for moving said means in one direction, means for limiting movement of said controlling means in said one direction thereby to position said

- 5 controlling means to allow a minimum predetermined flow of fuel to the burner for a low fire operation, means for moving said controlling means in a second direction for increased flow of fuel to the burner, means limiting movement
 10 of said controlling means in said second direction for determining a predetermined higher flow of fuel to the burner, means operable upon movement of said controlling means in said one direction and at a fuel flow intermediate to said
 15 predetermined minimum flow and said predetermined higher flow to cause said controlling means to hesitate at a predetermined intermediate position for a predetermined time in its movement in said one direction, and means for moving said controlling means with a snap action from said intermediate flow position to said minimum flow position subsequent to said predetermined time interval.

17. In an oil burner control system, means
 25 movable for controlling flow of fluid fuel, means for moving said means, means for limiting movement of said controlling means in one direction thereby to allow at least a minimum predetermined flow of fuel to the burner for low fire operation,
 30 said controlling means being movable in a second direction for increased flow of fuel to the burner, means limiting movement of said controlling means in said second direction for determining a predetermined higher flow of fuel to the burner, means operable upon movement of
 35 said controlling means in said one direction and at a fuel flow intermediate to said predetermined minimum flow and said predetermined higher flow to cause said controlling means to hesitate for a predetermined time in its movement in said one direction, and means for moving said second-named limiting means to allow said controlling means to be moved further in said second direction thereby to allow a predetermined maximum flow of fuel to the burner greater than said predetermined higher flow.

18. In an oil burner control system, means
 40 movable for controlling flow of fluid fuel, means for moving said means, means for limiting movement of said controlling means in one direction thereby to allow a minimum predetermined flow of fuel to the burner for low fire operation, said controlling means being movable in a second direction for increased flow of fuel to the burner,
 45 means limiting movement of said controlling means in said second direction for determining a predetermined higher flow of fuel to the burner, means operable upon movement of said controlling means in said one direction and at a fuel flow intermediate to said predetermined minimum flow and said predetermined higher flow to cause said controlling means to hesitate in its movement in one of said directions, and means sensitive to the effect of the output of the burner for controlling said second-named moving means.

19. In an oil burner control system, means
 50 movable for controlling flow of fluid fuel, means for moving said means, means for limiting movement of said controlling means in one direction thereby to allow a minimum predetermined flow of fuel to the burner, said controlling means being movable in a second direction for increased flow of fuel to the burner, means limiting movement of said controlling means in said second

direction for determining a predetermined higher flow of fuel to the burner, means for supplying air to the burner under pressure, and means operable upon movement of said controlling means and at a fuel flow intermediate said predetermined minimum flow and said predetermined higher flow to cause said controlling means to hesitate for a predetermined time in its movement in said one direction.

20. In an oil burner control system, means movable for controlling flow of fluid fuel, means for moving said means, means for limiting movement of said controlling means in one direction thereby to allow a minimum predetermined flow of fuel to the burner, said controlling means being movable in a second direction for increased flow of fuel to the burner, means limiting movement of said controlling means in said second direction for determining a predetermined higher flow of fuel to the burner, means for supplying air to the burner under pressure, means controlling said air supplying means, means interconnecting said flow controlling means and said second-named controlling means and operable upon movement of said flow controlling means to control said air supplying means, and means operable upon movement of said controlling means and at a fuel flow intermediate said predetermined minimum flow and said predetermined higher flow to cause said controlling means to hesitate for a predetermined time in its movement in said one direction.

21. In an oil burner control system, means movable for controlling flow of fluid fuel, means for moving said means, means for limiting movement of said controlling means in one direction thereby to allow at least a minimum predetermined flow of fuel to the burner for low fire operation, said controlling means being movable in a second direction for increased flow of fuel to the burner, means limiting movement of said controlling means in said second direction for determining a predetermined higher flow of fuel to the burner, means for supplying air to the burner under pressure, means operable upon movement of said controlling means in said one direction and at a fuel flow intermediate said predetermined minimum flow and said predetermined higher flow to cause said controlling means to hesitate in its movement in said one direction, and switch means responsive to the output of said air supplying means operable to render said second-named moving means ineffective upon failure of said air supplying means.

22. In an oil burner control system, means movable for controlling the flow of fluid fuel, means for moving said means, means for limiting movement of said controlling means in one direction thereby to allow a minimum predetermined flow of fuel to the burner for low fire operation, said controlling means being movable in a second direction for increased flow of fuel to the burner, means limiting movement of said controlling means in said second direction for establishing a predetermined higher flow of fuel for high fire operation of the burner, means for supplying air to the burner under pressure, means limiting the output of said air supplying means to that required for said low fire operation of the burner, means for moving said limiting means to increase the output of said air supplying means thereby to allow said air supplying means to supply air at a predetermined higher rate for said high fire operation, means operable upon movement of said controlling means in said one di-

rection and at a fuel flow intermediate said predetermined minimum flow and said predetermined higher flow to cause said controlling means to hesitate for a predetermined time in its movement in said one direction, and switch means responsive to the output of said air supplying means and operable to render said first-named moving means ineffective upon failure of said air supplying means to supply air at said predetermined higher rate.

23. In an oil burner control system, a liquid fuel burner, valve means controlling the supply of fuel to said burner, spring means urging said valve means toward open position, electrically heated bimetallic power means operatively connected to said valve means and operable to move said valve means toward closed position in opposition to said spring means, electrically operated fan means supplying air to said burner, switch means, means movable by said power means for controlling said switch means, means exerting a force tending to move said last-named means in opposition to the valve closing movement of said power means, means limiting movement of said switch actuating means in its opposing movement, means electrically connecting said switch means and said fan means for control of said fan means by said switch means, switch means controlling said power means, and heat actuated means positioned in heat transfer relationship with the output of said fan means and cooled thereby, said last-named means being operable upon failure of said fan means to heat up and operate said power means.

24. In an apparatus of the character described, a first reciprocally movable controlling member having a shoulder, a second reciprocally movable member having a shoulder, a first spring means urging said first member in one direction, a second spring means urging said second member in said one direction, power means having an arm engageable with said shoulders and exerting a force sufficient to move said reciprocally movable members in a second direction against the force of said first and said second spring means, means limiting movement of said reciprocally movable members in said second direction, said power means being operable to exert a progressively decreasing force thereby to allow said movable members to move in said one direction, means limiting movement of said second movable member in said one direction, and means limiting movement of said first movable member in said one direction, said last-named limiting means being so positioned relative to said second-named limiting means that said first movable member can have movement subsequent to limitation of movement of said second movable member upon sufficient decrease in force of said power means subsequent to limitation of movement of said second movable member.

25. In an apparatus of the character described, a first reciprocally movable member having a shoulder, a second reciprocally movable member having a shoulder, a first spring means urging said first member in one direction, a second spring means urging said second member in said one direction, power means having an arm engageable with said shoulders and operable to move said reciprocally movable members in a second direction against the force of said first and said second spring means, means limiting movement of said reciprocally movable members in said second direction, said power means being operable to exert a progressively decreasing

force thereby to allow said movable members to move in said one direction, means limiting movement of said second movable member in said one direction, and means limiting movement of said first movable member in said one direction, said last-named limiting means being so positioned relative to said second-named limiting means that said first movable member can have movement subsequent to limitation of movement of said second movable member upon sufficient decrease in force of said power means subsequent to limitation of movement of said second movable member, said second spring means being so constructed and arranged relative to said first spring means and said power means that the sum of the forces exerted by said first and said second spring means upon initial movement of said movable members in said one direction will continually exceed the opposing force exerted by said power means prior to engagement of said second movable member with said first-named limiting means so that said movable members will be moved in said one direction with a quick action.

26. In an apparatus of the character described, a first reciprocally movable member having a shoulder, a second reciprocally movable member, an abutment member carried by said second movable member and having a shoulder, a first spring means urging said first member in one direction, a second spring means urging said second member in said one direction, power means having an arm engageable with said shoulders and operable to exert a sufficient force to move said reciprocally movable members in a second direction against the force of said first and said second spring means, said power means being operable to exert a progressively decreasing force thereby to allow said movable members to move in said one direction, means for moving said abutment member relative to said second movable member thereby to adjust the limit of movement of said power means in said second direction, means limiting movement of said second reciprocally movable member in said first and said second direction, and means limiting movement of said first movable member in said one direction, said last-named limiting means being so positioned relative to said first-named limiting means that said first movable member can have movement subsequent to limitation of movement of said second movable member in said one direction upon sufficient decrease in force of said power means.

27. In an apparatus of the character described, a first reciprocally movable member having a shoulder, a second reciprocally movable member having a shoulder, a lever member having a portion in the path of movement of said second movable member, resilient means operatively connected to and urging said lever member into engagement with said second movable member and acting to urge said second movable member in one direction, spring means urging said first member in said one direction, power means having an arm engageable with said shoulders and operable to exert a sufficient force to move said reciprocally movable members in a second direction against the force of said spring means and said resilient means, said power means being operable to exert a progressively decreasing force thereby to allow said movable members to move in said one direction, means limiting movement of said reciprocally movable members in said second direction, means limiting movement of said second movable member in said one di-

rection, and means limiting movement of said first movable member in said one direction, said last-named limiting means being so positioned relative to said second-named limiting means that said first movable member can have movement subsequent to limitation of movement of said second movable member upon sufficient decrease in force exerted by said power means.

28. In an apparatus of the character described, 10 a casing having a first chamber for liquid with an outlet, said casing having a second chamber, valve means movable relative to said outlet to control flow of liquid from said first chamber and having a portion extending into said 15 second chamber, said valve means having an abutment, spring means surrounding said valve means and interposed between said abutment and the wall of said first chamber adjacent said outlet and acting to move said valve means in 20 an open direction, said valve means having a shoulder within said second chamber, a reciprocal member within said second chamber and having a shoulder, bimetallic heat actuated means secured to said casing within said second chamber and having an arm engageable with said shoulders, means urging said reciprocal member in one direction, said bimetallic means being operable at normal temperatures to move said valve means toward closed position and said reciprocal member in a second direction opposite to said one direction, electric means for heating said bimetallic means to a higher temperature than normal, said bimetallic means when at said higher temperature being moved by said spring 35 means and said urging means to allow movement of said valve means in an open direction and said reciprocal member in said one direction, stop means limiting movement of said valve means in valve open direction, and stop means 40 limiting movement of said reciprocal member in said one direction and so constructed and arranged relative to said first-named stop means that said reciprocal member is limited in its movement in said one direction prior to limitation of movement of said valve means in said valve open direction.

29. In an apparatus of the character described, a casing having a first chamber for liquid with an outlet, said casing having a second chamber, valve means movable relative to said outlet to control flow of liquid from said first chamber and having a portion extending into said second chamber, said valve means having an abutment, spring means surrounding said valve means and interposed between said abutment and the wall of said first chamber adjacent said outlet and acting to move said valve means in an open direction, said valve means having a shoulder within said second chamber, a reciprocal member within said second chamber, said reciprocal member being movable between predetermined limits, an abutment carried by said reciprocal member, means for moving said abutment relative to said reciprocal member, bimetallic heat actuated means secured to said casing within said second chamber and having an arm engageable with said shoulder and said abutment, means urging said reciprocal member in one direction, said bimetallic means being operable at normal temperatures to move said valve means toward closed position and said reciprocal member in a second direction opposite to said one direction, electric means for heating said bimetallic means to a higher temperature than normal, said bimetallic means when at said higher temperature being

moved by said spring means and said urging means to allow movement of said valve means in an open direction and said reciprocal member in said one direction, and stop means limiting movement of said valve means in valve open direction and so constructed and arranged relative to said predetermined movement of said reciprocal movement that said reciprocal member is limited in its movement in said one direction prior to limitation of movement of said valve means in said valve open direction.

30. In an apparatus of the character described, a first reciprocally movable member movable in a first and a second direction, a second reciprocally movable member movable in said first and said second directions, means engageable by and for limiting movement of said second member in said first and said second directions, means engageable by and for limiting movement of said first member in said first direction, means urging each of said members in said first direction and into engagement with their respective limiting means, and power means operable to exert a progressively increasing force thereby to move said members in said second direction against the force of said urging means, said limiting means being so constructed and arranged relative to each other that when said members are engaging their respective limiting means said power means must move said first member a predetermined distance in said second direction prior to movement of said second member in said second direction by said power means.

31. In an apparatus of the character described, a first reciprocally movable member movable in a first and a second direction, a second reciprocally movable member movable in said first and said second directions, means engageable by and for limiting movement of said second member in said first and said second direction, means engageable by and for limiting movement of said first member in said first direction, means urging each of said members in said first direction and into engagement with their respective limiting means, bimetallic means operable to exert a progressively increasing force upon increase in temperature thereby to move said members in said second direction against the force of said urging means, and means to heat said bimetallic means, said limiting means being so constructed and arranged relative to each other that when said members are engaging their respective limiting means and said bimetallic means is heated, said bimetallic means must move said first member a predetermined distance in said second direction prior to movement of said second member in said second direction by said power means thereby to cause said first member to hesitate in its movement in said second direction until the force exerted by said bimetallic means has in-

creased sufficiently to overcome the added force of said second member urging means.

32. In an apparatus of the character described, a movable controlling member having a range of movement, power means acting on said member and holding said member at one limit of said range, means urging said movable member against the force of said power means, thrust means acting against said power means and in

10 conjunction with said urging means, said urging means and said thrust means determining the reduction of force of said power means at which said urging means will move said movable member, and means operable within said range to 15 limit the action of said thrust means against said power means so that said power means must have a further reduction of force prior to continuation of movement of said movable member by said urging means.

20 33. In an oil burner control apparatus, fuel supply means, means to regulate the rate of fuel flow from said means, means to supply air under pressure for combustion, means to control said regulating means to increase the flow rate upon 25 demand for heat, means operable upon said increase to render said air pressure means effective to supply air for a flow rate in excess of said increased rate, and means to delay further increase in the flow rate for a period subsequent 30 to the rendering of said pressure means effective.

34. In an oil burner control apparatus, fuel supply means, means to regulate the rate of fuel flow from said means, means to supply air for combustion, means to control said regulating 35 means to decrease the flow rate upon cessation of demand for heat, and means operable after an interval of maintained constant decreased fuel flow subsequent to said decrease to decrease the quantity of air supplied by said supply means.

40 35. In an apparatus of the character described, a movable controlling member, means resisting movement of said member and having its resisting force decreasing during a time interval, means to move said member in opposition to said resisting means, means operable within the range of 45 movement of said movable member to decrease the force exerted by said moving means to a force less than the force exerted by said resisting means, and means acting to hold said member against movement by said resisting means during the period when said resisting means force exceeds the force exerted by said moving means, said resisting means having its force decreasing subsequent to operation of said operable means 50 to a force less than the decreased force of said moving means so that said moving means is operable to continue the movement of said member.
